UNITED STATES PATENT OFFICE

JOHN J. YAZUM, OF AMSTERDAM, NEW YORK

TOURIST'S CABINET

Application filed July 3, 1928. Serial No. 290,090.

The present invention is directed to improvements in tourists' cabinets.

The primary object of the invention is to provide a device of this character so constructed that it can be detachably attached to the running board of an automobile, in order that it can be conveniently removed and carried to any location.

Another object of the invention is to provide a device of this kind so constructed as to provide compartments in which articles of food, as well as cooking utensils and a vacuum jug or the like can be compactly stored therein.

Another object of the invention is to provide a cabinet of this nature constructed in such manner that it can be secured to the running board of an automobile without interfering with the opening and closing of the door of the vehicle.

With these and other objects in view, this invention resides in the novel features of construction, formation, combination and arrangement of parts to be hereinafter more fully described, claimed and illustrated in the accompanying drawings, in which:—

Figure 1 is a side elevation of the cabinet showing the same in place.

Figure 2 is a longitudinal sectional view therethrough.

Figure 3 is a sectional view on line 3—3 of Figure 2.

Figure 4 is a sectional view on line 4—4 of Figure 2.

Figure 5 is a sectional view on line 5—5 of Figure 1.

Figure 6 is a sectional view on line 6—6 of Figure 2.

Figure 7 is a fragmentary top plan view.

Referring to the drawings 1 designates a cabinet which consists of compartments 2 and 3, the former has a flat bottom 4 which rests upon the running board 5, while the bottom 5' of the latter, which is a continuation of the bottom 4, is curved to conform to the curvature of the fender 6. The compartment 2 has connected thereto by hinges 7 a cover 8, a similarly connected cover 9 being provided for the compartment 3. The respective covers can be locked in any appropriate manner.

The compartment 2 is relatively large in order to receive sandwiches, fruit, containers for various articles of prepared food and other edibles.

The compartment 3 has fixed therein a vertical partition 10 which has its lower edge resting upon a horizontal partition 11, said partition forming in conjunction with the wall 12, a compartment 13, said compartment serving to contain bottles of milk, water, drinking glasses or any other articles necessary to complete the outfit.

The partition 11 is of such width that a space 14 is provided between its forward edge and front wall 15. The partition 10 is spaced from the wall 15 and fixed to the sides 16—16 are strips 17—17, the strips and the partition 11 defining the compartment 18, and since the strips are comparatively narrow a frying pan or the like can be readily placed in this compartment without interfering with the strips.

A vacuum jug can be placed in the compartment 3 and will rest upon the strips 17—17. The partition 10 is of such height that a tray 19 can be conveniently placed in the upper end of the compartment 3 and will rest upon the upper edge of said partition, the cover 9 closing the tray. In this tray may be placed cups, plates, knives, forks and salt and pepper containers.

The bottom 4 has secured thereto a pair of plates 20 through which are passed clamping bolts 21 to aid in securing the cabinet to the running board.

The wall 15 has bolted thereto a plate 22, said plate having a flange 23 carried thereby in which is engaged a clamping bolt 24, said bolt being extended for engagement in the adjacent side sill 25 of the vehicle. This bolt will obviously maintain the forward side of the cabinet securely upon the running board.

From the foregoing, it is thought that the construction, operation and many advantages of the herein described invention will be apparent to those skilled in the art, without further description, and it will be understood that various changes in the size, shape, and proportion and minor details of construction, may be resorted to without departing from

the spirit or sacrificing any of the advantages of the invention.

What is claimed is:—

A cabinet to be secured upon the running board of an automobile comprising a body of sufficient height for a portion of its length to fit beneath the door of the automobile and having its other end portion extending upwardly, an inner side wall of the last-mentioned end portion extending downwardly to form a partition dividing the body into a shallow compartment and a deep compartment, covers for said compartments movable into and out of closing relation thereto, partitions in the deep compartment defining an auxiliary chamber having its upper end spaced from the top of the compartment, and a main chamber at one side thereof having its lower portion extending beneath the auxiliary chamber, ledges projecting from opposed walls of the main chamber above the bottom of the auxiliary chamber and dividing the main chamber into upper and lower portions communicating between the ledges, and a removable tray in the deep compartment closing upper ends of the main chamber and auxiliary chamber when in place.

In testimony whereof I affix my signature.

JOHN J. YAZUM. [L. s.]
